UNITED STATES PATENT OFFICE

HENRY HUEBER, OF BUFFALO, NEW YORK, ASSIGNOR TO TRICO PRODUCTS CORPORATION, OF BUFFALO, NEW YORK

WINDSHIELD CLEANER

Application filed March 20, 1930. Serial No. 437,573.

This invention relates to improvements in fluid pressure operated windshield cleaners of the type disclosed in my Patent No. 1,697,358 granted Jan. 1, 1929.

5 The construction of the cleaner disclosed in this patent embodies a fixed piston over which moves a reciprocating cylinder carrying to one side thereof a wiper supporting structure. Means are provided for guiding 10 this structure and holding the cylinder from rotation about the piston. The drawings of the patent depict this means as comprising a taut wire or rod stretched substantially parallel to the path of the cylinder and passing through the tubular part of the structure whereby said part would slide along the wire as the cylinder reciprocated. Being subject to rust and the collection of dust thereon, the wire required considerable attention 15 in order to maintain the practical efficiency of the cleaner.

The present invention has for its primary object to improve the cleaner construction with respect to its guided movement, and it resides in the provision of guide means carried on the moving portion of the cleaner for acting in cooperation with a wall of the housing for defining the path of movement of such moving portion.

20 The invention will further be found to reside in the structural features of the cooperative guide elements, their association and mountings, as will appear more fully hereinafter, reference being had to the accompanying drawings wherein:

Fig. 1 is a perspective view with portions removed, depicting the improved windshield cleaner construction.

25 Fig. 2 is an enlarged fragmentary view showing portions in section and other parts in elevation for a clearer disclosure of the structural features and arrangements.

Fig. 3 is a transverse vertical section through the cleaner.

30 Fig. 4 is a detail sectional view through one of the guide roller mountings.

Referring more in detail to the accompanying drawings, the numerals 1 and 2 designate respectively the atmospheric and low pressure pipes leading to and supporting a cen-

trally disposed piston (not shown), and the numeral 3 designates the cylinder which encloses the piston and is slidably supported by the pipes 1 and 2 for reciprocatory movement as the source of low pressure or suction 55 is alternately applied to the opposite ends of the cylinder by the usual valve mechanism, all of which is more fully set forth in said patent.

The housing or casing 4 encloses the cylinder and pipes, the latter being extended through the ends of the housing for communication with the atmosphere and the source of low pressure. The lower side of the housing is provided with spaced depending flanges 60 65 5 constituting the walls of a slot or guide-way 6.

The wiper supporting structure comprises a carrier support 7 on which is mounted a pair of carriers 8, each provided with an 70 arm 9 for supporting a wiper blade 10. The carrier support 7 is suspended from the lower side of the cylinder by a pair of bracket arms 11. In practice the heads of the cylinder 3 are locked in place by bayonet and slot 75 connections indicated generally by the reference numeral 12, the lugs of these connections being carried by the heads and the lower lug of each head being extended to form the bracket arms 11 for suspending the supporting rod 7. Coiled springs 13 hold the wiper blades in firm wiping contact with the windshield glass, and by reason of the torsional stresses of these springs the cylinder is urged about its longitudinal axis, which movement 80 85 is resisted by the front wall 5 of the guide-way 6. In other words, this front wall serves to define the path or course of the wiper carrying structure.

Tracking on this front wall 5 are one or 90 more rollers 14, two of such rollers being herein depicted. Each roller is journaled in a fork or yoke 15 which is attached to an end of the support 7 in a manner to secure the support to its suspension brackets 11. In 95 the preferred showing the brackets 11 are provided with openings of a sufficient size to receive the adjacent ends of the support and the forks 15 are then secured to the ends of the support, over the brackets 11, to pre- 100

vent displacement of the support therefrom. The forks are preferably connected to their shanks or stems 16 in a swivel-like manner and at the base of the shanks are collars 17 having a larger diameter than the adjacent ends of the support 7 so as to overlie the brackets 11 and impinge against the ends of the support.

In assembling the guide rollers with the wiper carrying structure, the support 7 has its ends inserted in the brackets 11, and the shanks 16 are then attached to these ends as by being threaded thereinto, as shown in Fig. 4. The guide rollers therefore serve a triple office in first guiding the wiper carrying structure in its movement, second in securing this structure in its assembled relation, and third in resisting rotary movement of the cylinder.

20 In operation, the operating pressure is alternately applied to the ends of the cylinder 3 at opposite sides of its inclosed piston so as to reciprocate the cylinder and its wiper carrying structure, during which reciprocation 25 the guide rollers 14 track on the front wall of the housing slot 6. The wipers are therefore held firmly against the windshield glass throughout the extent of travel of the carriage.

20 What is claimed is:

1. A windshield cleaner comprising a reciprocatory support and wiper means carried thereby, a track fixed alongside of the path of movement of the support, and a guide member mounted on the support for tracking engagement with said track, said guide member swiveling about an axis substantially parallel with the track whereby said guide member will adjust and accommodate itself 40 to any unevenness in the track during reciprocatory movement of said support.

2. A windshield cleaner comprising a reciprocatory member having spaced brackets depending therefrom and formed with openings, an elongated supporting member having its ends engaged in the openings of said brackets for support, wiper carrying means on said supporting member, means engaging the ends of said supporting member for se-

50 curing the same against displacement from the openings of said brackets, guide means carried by said securing means, and a housing enclosing said reciprocatory member and having a guide surface on which said guide means have tracking engagement.

60 3. A windshield cleaner comprising a reciprocatory cylinder having a pair of depending brackets formed with openings therein, an elongated support having its ends engaged in the openings of said bracket for being supported by and from said cylinder, a guide roller at each end of the support having a mounting shank threaded into the adjacent end of the support and acting to secure the latter against displacement from the opening

of the adjacent bracket, wiper carrying means on said support, and a guide surface for being tracked by said rollers.

4. A windshield cleaner comprising a reciprocatory member, an elongated support carried thereby, wiper means arranged on the support adjacent each end thereof, a track fixed alongside of the path of movement of the support, and a guide roller arranged at each end of the support for tracking engagement with said track, each guide roller being mounted to swivel about an axis lengthwise of the path of movement of said support.

5. A windshield cleaner comprising a reciprocatory member having spaced brackets extending laterally and formed with registering openings, a wiper supporting member interposed between the brackets, means connected through the bracket openings with the opposite ends of the supporting member for securing the latter to the brackets, said means being engaged with the outer faces of said brackets, guide rollers carried by said means for swiveling about an axis lengthwise of the path of movement of said reciprocatory member, and a track extending alongside of said reciprocatory member for tracking engagement by said guide rollers.

6. A windshield cleaner comprising a reciprocatory member, a support carried thereby and provided at its opposite ends with screw threaded openings, guide rollers for said support, means for supporting each guide roller for movement about an axis transverse to the path of movement of said reciprocatory member, said means including a screw threaded shank engaged in the adjacent one of said screw threaded openings in said support, said screw threaded shank being engaged in its opening to permit swiveling movement of said roller mounting means about the axis of said shank, a track on which said rollers have tracking engagement, said track acting on said rollers to restrict and limit said roller mounting means against shank-dislodging movement, and wiper means carried by said support.
